CUSHIONING OF THE HANDLE OF
COMPRESSED AIR HAMMERS

Fritz Faudi, Dusseldorf-Oberkassel, Germany, assignor to A. Ehrenreich & Cie., Dusseldorf-Oberkassel, Germany, a partnership of Germany

Application November 29, 1932, Serial No. 644,880
In Germany May 21, 1932

8 Claims. (Cl. 267—1)

In the cushioning of the handle on compressed air hammers according to my patent application Ser. Nr. 600,506 the recoil of the main hammer housing relatively to the handle is cushioned by throttling the return of the compressed air to the compressed air mains and the consequent moderately rising increase in the compressed air tension increases the total braking pressure on the piston rod carrying the handle which piston rod carries a piston reciprocating in a cushioning cylinder in the hammer housing. The pressure is such that at the end of the possible cushioning path the cushioned members are separated from one another by a cushion of compressed air which is, as far as possible, so completely trapped that metal to metal contact is impossible, even when violent recoil has to be cushioned.

An object of the present invention is to provide a handle cushioning mechanism for pneumatic hammers providing a cushioning action which increases by successive steps.

The invention consists in providing cushioning mechanism comprising a cushioning piston reciprocably mounted in a cylinder in the pneumatic hammer housing, said cylinder having a compressed air inlet, a piston rod connecting the cushioning piston to the handle of the pneumatic hammer, and means cooperating with the piston during a cushioning stroke thereof for successively entrapping and compressing separate cushioning volumes of compressed air.

A simple example of construction of a handle-cushioning arrangement of this type is shown in the drawings.

Figures 1, 2, 2a, 2b, 3, 3a, 4 and 5 show several forms of construction partly in section of the arrangement, according to the invention.

Fig. 3a is a part sectional view taken on a plane at right angles to the plane of the section shown in Fig. 3.

Referring to Figure 1 a is the hammer housing containing the hammer mechanism, b is the hammer housing which surrounds the head chamber c and contains the cushioning compressed air. The transverse wall d separates the head chamber c from the main cylinder in the housing a.

The passage e connects the head chamber with the working air of the compressed air main or the compressor air accumulator. The plunger-like piston f carries the handle g. The piston f is shown to the left of the centre line in its extreme outward position, in which, by the compressed air loading its free piston sur-

face, it is pressed into the head chamber c and in which it is held when the hammer is connected with the main, but is not in operation. When violent oscillations of the parts cushioned by the compressed air occur, the piston f can pass into the position shown to the right of the centre line, namely the opposite extreme position. In this position it has passed beyond the shoulder b' formed at the end of the head chamber, and separates a part of the compressed air in the head chamber which in the meantime has been subjected to high tension, to form a true compressed air cushion between the end surface of the piston, the surface of the partition d and the walls of the cylinder formed at the narrowed part of the head chamber over this partition.

Now the invention consists in that, without detriment to the presence of the compressed air cushion, when very great oscillations of the parts occur, such a cushion is formed even sooner in the course of the travel of the piston relative to the housing, when both parts, as the hammer is pressed or being operated, are moved towards each other. The separation of the compressed air for the special compressed air cushion, may occur at the beginning of the relative movement of the piston, just after or when it is in a centre position.

According to Figure 2 the special compressed air cushion comes into operation for example, not in the first moment of the movement, but when it has proceeded a certain amount. Left of the centre line, the relative initial position of the parts is shown, and on the right the final position. The piston contains the cylindrical cavity h which is coaxial with an auxiliary piston f' fixed on the partition d. If one imagines, in the cushioning, the piston f moving relatively from the initial to the final position, then the whole piston area is loaded at first by the compressed air in the head chamber. Then the compressed air is shut off from a part of the piston by the entry of the auxiliary piston f' in the piston cavity h, and on the further forward movement of the piston, is compressed as a compressed air cushion. Its resisting pressure increasing progressively is added to the thrust which results from the free piston surface and the moderately increasing air pressure in the head chamber. When the piston reaches the projection b' at the end of the head chamber, the final compressed air cushion is formed as described with reference to Figure 1, and the total loading of the piston is now composed of

the effect of this final compressed air cushion and the additional compressed air cushion which has already previously become effective in the cavity h of the piston f . The elements serving to form this additional compressed air cushion, the cavity h and the auxiliary piston f' may, of course, also be arranged in a reverse order to that described—the piston f' can be fixed to the main piston f and the cavity h may be arranged 10 in the partition d , as shown in Fig. 2b.

The two members may also, at the outset, overlap each other in such a manner that the piston f' even in the initial position, is entered in the cavity h .

15 The inter-engagement of the two parts than at the same time serves for the mutual guiding and for efficient trapping of the compressed air in the cavity h from the beginning. The trapping is in any case favored by the cylindrical 20 smooth walls and by the possibility thereby presented of exact construction and fitting. Figure 2 shows this form of construction. The original connection between the quantity of compressed air separated for forming the cushion 25 ion and the compressed air contained in the head chamber is established by a central boring in the auxiliary piston f' and by passages leading radially therefrom in one plane and at a distance from the end of the auxiliary piston f' 30 and passing through the piston or the like. Its outlet position, that is, the movement in which it is lapped by the inner casing surface of the hollow cylinder h , then decides the beginning of the action of the compressed air cushion introduced into it.

35 In the embodiment of the invention according to Figures 2 and 2a already described it was assumed that only one of the final compressed air cushions was introduced. Two or more additional compressed air cushions may be introduced, of which one after the other is formed at previously determined distances and whereby those freshly produced in each case comes into operation therewith or with that previously 45 formed.

40 In this arrangement the same members suitable for forming a compressed air cushion, as described above, may be used, namely so that besides those located coaxially with the centre line of the hammer, or without such, similar pairs of members are arranged distributed about the centre line of the relatively movable parts facing one another. Figs. 3 and 3a show an example. In this case four cylindrical bores 50 are formed in the piston and opposite them on the separating floor four suitably formed solid cylinders f' are rigidly mounted. According to the example the construction is such that the bores and the solid cylinders are arranged symmetrically in pairs with respect to the longitudinal axis of the head chamber, each bore of one pair and consequently each cylinder of the corresponding pair of cylinders being arranged diametrically. In the formation of the compressed 55 air cushion first one pair come into operation followed by the other pair when the piston has travelled a predetermined distance in relation to the housing.

60 Instead of the compressed air cushioning elements being distributed over the surface of the piston or of the partition forming the floor of the head chamber, and constructing the compressed air cushioning elements as separate members in the form of cylindrical bores and 65 cylindrical bodies filling them the same purpose

is advantageously attained and the manufacture of the parts is facilitated, by the pairs of elements serving to form two or more compressed air cushions before the formation of the final compressed air cushion, being formed as annular cylindrical recesses and projections, which surround each other concentrically.

80 Such forms of construction are shown in Figure 4. Figure 5 also shows an example of this. In Figure 4 the projections and the recesses are separated from each other annularly and in Figure 5 they form step-like shoulders.

85 The two examples according to Figures 4 and 5 show, moreover, a form of construction in which the arrangement of additional compressed air cushions is used wherein a differential piston, by means of a trick piston rod, carries the handle. In this arrangement the piston head of the differential piston divides the head chamber containing the compressed air into two 90 chambers, the main cushioning chamber c' on the free surface and the damping chamber c'' on the surface reduced by the piston rod.

95 I claim:

100 1. A handle cushioning mechanism comprising a cushioning cylinder having a compressed air inlet, a piston reciprocably mounted in the cylinder, a piston rod connecting the cushioning piston with the handle, a shoulder in the cylinder arranged between its lower end and the inlet, 105 said shoulder cooperating with the piston to entrail a cushioning volume of compressed air, a plug extending upwardly from the bottom of the cushioning cylinder and permanently engaging a corresponding cavity in the bottom of the 110 cushioning piston, said plug having a port permitting compressed air to enter said cavity during the first portion of a cushioning stroke of the piston and being sealed by said piston to entrail a separate volume of cushioning air in 115 said cavity before the piston reaches the shoulder.

120 2. A handle cushioning mechanism comprising a cushioning cylinder having a compressed air inlet, a piston reciprocably mounted in the cylinder, a piston rod connecting the cushioning piston with the handle, a shoulder in the cylinder arranged between its lower end and the inlet, 125 said shoulder cooperating with the piston to entrail a cushioning volume of compressed air, a plurality of concentrically arranged projections of different height in the bottom of the cushioning cylinder cooperating with a plurality of corresponding concentrically arranged cavities in the bottom of the cushioning piston to successively entrail separate cushioning volumes of compressed air before the piston reaches the shoulder.

130 3. A handle cushioning mechanism comprising a cushioning cylinder having a compressed air 135 inlet, a piston reciprocably mounted in the cylinder, a piston rod connecting the cushioning piston with the handle, a shoulder in the cylinder arranged between its lower end and the inlet, 140 said shoulder cooperating with the piston to entrail a cushioning volume of compressed air, a stepped auxiliary piston arranged in the bottom of the cushioning cylinder and cooperating with a corresponding stepped cavity in the bottom of the cushioning piston to successively entrail separate cushioning volumes of compressed air before the first mentioned piston reaches the shoulder.

145 4. A handle cushioning mechanism comprising a cushioning cylinder having a compressed 150

- air inlet, a main piston reciprocably mounted in the cylinder and having a cavity therein, a piston rod connecting the cushioning piston with the handle, and an auxiliary piston in the cylinder cooperating with the cavity in the first-mentioned main piston, said cylinder having means therein so that the auxiliary piston and the cavity form a separate cushioning volume of compressed air before the main piston makes an air cushion in the cylinder by the elimination of the influence of the compressed air inlet in the cylinder. 5
5. A handle cushioning mechanism comprising a cushioning cylinder having a compressed air inlet, a piston reciprocably mounted in the cylinder and forming therewith the parts to be cushioned, a piston rod connecting the cushioning piston with the handle, a shoulder in the cylinder placed between its lower end and the inlet, said shoulder cooperating with the piston to entrap a cushioning volume of compressed air, and an auxiliary piston on and a cooperating cavity in said parts to be cushioned so arranged that the auxiliary piston will enter the cavity and entrap therein a separate cushioning volume of compressed air before the first-mentioned piston reaches the shoulder. 10
6. A handle cushioning mechanism comprising a cushioning cylinder having a compressed air inlet, a piston reciprocably mounted in the cylinder, and an auxiliary piston in the cylinder cooperating with the piston and a cavity into which it fits, said cylinder having means therein so that the auxiliary piston and the cavity form a separate cushioning volume of compressed air before the main piston makes an air cushion in the cylinder by eliminating the influence of the compressed air inlet in the cylinder. 15
7. A handle cushioning mechanism according to claim 6, in which the auxiliary piston is of smaller diameter than the diameter of the main piston. 20
8. A handle cushioning mechanism comprising a cushioning cylinder having a compressed air inlet, a piston reciprocably mounted in the cylinder, and an auxiliary piston in the cylinder cooperating with the piston and a cavity into which it fits, said cylinder having means therein so that the auxiliary piston and the cavity form a separate cushioning volume of compressed air before the main piston makes an air cushion in the cylinder by eliminating the influence of the compressed air inlet in the cylinder. 25
